UNITED STATES PATENT OFFICE.

HERBERT L. DELANEY, OF SAN FRANCISCO, CALIFORNIA, ASSIGNOR TO BUNTING IRON WORKS, OF SAN FRANCISCO, CALIFORNIA, A CORPORATION OF CALIFORNIA.

ROTARY OIL BURNER.

Application filed May 8, 1923. Serial No. 637,433.

To all whom it may concern:

Be it known that I, HERBERT L. DELANEY, a citizen of the United States, and a resident of the city and county of San Francisco, in 5 the State of California, have invented a new and useful Rotary Oil Burner, of which the following is a specification.

This invention relates to an oil burner, and more particularly to such a burner that 10 sprays the liquid fuel by the aid of centrifugal force. This force may be produced by rotating a cup into which the liquid fuel is dripped. The sprayed fuel is in a proper condition for combustion for producing heat. 15 The heat may be used for generating steam and for other well-known purposes.

In such arrangements it is customary to provide for a fairly strong blast of air or other gas, such as steam, past the edges of 20 the rotating cup so as to project the fuel spray into the combustion chamber, and also to supply at least a portion of the oxygen for supporting the combustion. It has been proposed to create this blast by either of two 25 methods—either by a fan structure which is made a part of the burner, or else by conducting air or other gaseous fluid under pressure through appropriate passageways past the cup. It is one of the objects of my in- 30 vention to provide a blast for an oil burner in a novel manner that is more economical than either of the schemes mentioned.

Another object of my invention is to improve and simplify in general an oil burner 35 structure.

In one type of oil burner the blast of air or other gaseous fluid is utilized to rotate the cup, by the aid of appropriately formed turbine blades. In this way no separate source 40 of power need be provided for effecting this rotation. My invention may be very readily utilized in connection with a burner of this character, as well as with the usual type where the cup is motor driven.

45 My invention possesses other advantageous features, some of which with the foregoing will be set forth at length in the following description, where I shall outline in full that form of the invention which I have 50 selected for illustration in the drawings accompanying and forming part of the present specification. Although in the drawings I have shown but one embodiment of my invention, I do not desire to be limited thereto,

since the invention as expressed in the claims 55 may be embodied in other forms also.

Referring to the drawings:

Figure 1 is a front elevational view of an oil burner embodying my invention, as installed near the wall of a combustion chamber;

Fig. 2 is a longitudinal sectional view of the oil burner;

Fig. 3 is a sectional view along the plane 3—3 of Fig. 2; and

Fig. 4 is a sectional view along plane 4—4 of Fig. 2.

A section of the combustion chamber wall 11 is indicated in Fig. 1 of the drawings, on which wall may be appropriately supported 70 the burner structure. In the present instance this structure is supported on hollow hinge-pins 12 and 13 which also serve conveniently as conduits for the oil and air, in a manner that will be described in detail hereinafter. These pins 12 and 13 pass through the cooperating lugs 14 and 15, the lugs 14 being attached in any appropriate manner to the wall 11, and the lugs 15 to the supporting member 16; this member is so formed that the burner casing 17 of general tubular shape, may be projected through the opening 18 in the wall 11 by swinging the support 16 on the hinge pins 12 and 13. Although from this point on I shall refer to the medium under pressure as air, it will be understood that my invention is not to be limited to the use of air only, since the same benefits may be derived by using other kinds of gases under pressure; for example, such as steam.

90 In the present instance the oil cup 19 of conical form is fastened as by the inter-engaging threads 20 to a rotatably mounted sleeve 21. This sleeve has spiral shaped 95 vanes or propellers 22 extending from its outside surface, so that it may be rotated by a fluid current directed against the vanes. The sleeve 21 is rotatably supported by the aid of the ball bearings 23 interposed between the interior of sleeve 21 and the stationary rod 24. This rod may in turn be integrally attached to a member 25 which is screwed into the boss 26 formed on a cross piece 27, extending across the interior of the tubular casing or frame 17. The races 28 for the ball bearings 23 are maintained in spaced relation on rod 24 by the aid 100 105

of the sleeve 29, and both these races and the sleeve are clamped tightly on rod 24 between a shoulder 30 and the nuts 31. Furthermore axial movement of the rotatably mounted tube 21 may be prevented in any appropriate manner, as by the aid of the flange 32 formed at the end of the tube.

The rotatable structure just described may take other forms, since its particular details 10 form no part of my present invention; and in fact it is possible to adapt my invention to a construction where the cup 19 is rotated not by an air blast but by an auxiliary motor.

15 The supply of oil to the interior of cup 19 is effected through the pipe 33 which communicates with an aperture 34 in the member 27; this aperture in turn communicates with the axial bore 35 through the 20 members 25 and 24. Member 24 extends into the cup and carries at its end the drip tube 36 which deposits the oil on the interior surface of cup 19.

That portion of the oil burner structure 25 which appertains to the supply of a gaseous fluid blast past the edge of cup 19 will now be described. For this purpose I use compressed air or other gaseous fluid under pressure, and discharge it at relatively high 30 pressure into a conduit that is open to the atmosphere. In this way the fluid due to its velocity at discharge, serves to suck in a great deal of air into the conduit from the surrounding atmosphere, and the resultant 35 greatly increased volume of gaseous fluid at comparatively low pressure is conducted through appropriate passageways past the cup exterior. Although this mode of operation may be accomplished by a wide 40 variety of apparatus, I prefer to utilize the devices illustrated, in which a pipe 37, connected to a source of fluid under pressure, leads this fluid into an open ended tubular member 38. This member has a flared 45 mouth 39 where the gaseous fluid enters, which is bridged by a strap 40. This strap serves merely as a support for the pipe 37, as by the aid of the boss 41 into which the pipe 37 is screwed. Furthermore an injector nozzle 42 may if desired be utilized 50 for ensuring a high velocity of discharge of the fluid under pressure from pipe 37, with an attendant great suction effect on the air coming in through the mouth 39.

55 The member 38 is so designed that the proper expansion and attendant reduction in pressure take place therein for the fluid discharged from pipe 37. Furthermore the discharge end 43 of this member is connected 60 to the frame 17 near the structure for rotatably supporting the cup. The fluid at relatively low pressure and of considerable volume is conducted past the propellers 22, and is confined for this purpose by the aid 65 of a tubular nozzle 44 of the desired con-

figuration. This nozzle may be conveniently supported on the casing 17, as by the aid of screw threads 45. The open end 46 of the nozzle serves to form a constricted narrow passageway for the fluid past the end of cup 19, and the sprayed fuel is projected by this fluid blast into the combustion chamber. At the same time this blast also serves, by impinging against the propellers 22, to rotate the cup. In order to 70 guide the fluid blast into the annular space formed between the nozzle 44 and the rotating sleeve 21, a conical deflector 47 is provided where the fluid leaves the member 75 38.

The piping for the oil pipe 33 and the pipe 37 from the hinge conduits 12 and 13 is illustrated in Fig. 1. The connections 48 and 49 are so arranged with respect to the 80 conduit hinges 12 and 13 that rotation of the support 16 about these hinge pins is permitted.

The blast of gas, such as air or steam as produced in the way outlined has many advantages. It is possible to use air or steam at relatively high pressure. By sucking in additional air through the open mouth 39 of tube 38, and by permitting the fluid to expand, the pressure is reduced to the desired value while its volume is correspondingly greatly increased. If compressed air or high pressure steam alone were used without the aid of the additional air taken in at the mouth 39, a comparatively low pressure would have to be used in order to 90 secure the best results with the burner. It is uneconomical to provide such low air or steam pressure. On the other hand, the device described may use high pressure air or steam in a very economical manner; the drawing in of additional air by permitting it to expand in the tube 38 makes the resultant blast have the right velocity and pressure. It has been found by actual experiment that such an arrangement as described 95 may serve to draw in a volume of air from the surrounding atmosphere that is several times greater than that actually taken from the compressor. The quantitative effects of the device may obviously be varied by properly proportioning the elements therein. 100

110 It is also understood that the oil supplied through pipe 33 may be pumped by any appropriate arrangement external of the apparatus shown. Likewise any convenient form of air compressor or other source of fluid pressure may be utilized to supply the fluid through the pipe 37. 115

I claim:

120 1. In an oil burner, a rotatable oil cup for spraying fuel supplied thereto, and means for providing a blast of gaseous fluid to the combustion chamber, comprising a hollow member forming an expansion chamber coaxial with said combustion chamber, 125 130

- said member being open at one end, and means centrally positioned within said open end for conducting gaseous fluid under pressure into the chamber near its open end, whereby the released fluid may serve to draw in air through the open end.
2. In an oil burner, a rotatable oil cup for spraying fuel supplied thereto, means adapted to be operated by a blast of gaseous fluid for rotating the cup, and means for producing a blast of gas for rotating the cup and for projecting the fuel into a combustion chamber, comprising means forming an open ended chamber, means for releasing gaseous fluid under pressure near the open end of the chamber in such a manner as to draw in air through the open end, and a means for conducting the fluid past the cup rotating means and the end of the cup.
3. In an oil burner, a rotatable oil cup, a nozzle surrounding the cup and forming a discharge passage past the cup for a blast of gaseous fluid, a member of tubular form connected to the nozzle, said member having an opening at its free end to the atmosphere coaxial with said passage, and means centrally positioned in said opening for conducting a gaseous fluid under pressure into the member so as to draw in air through the opening.
4. In an oil burner, a rotatable oil cup, a nozzle surrounding the cup and forming a discharge passage past the cup for a blast of gaseous fluid, a tubular member having flaring ends, one of said ends being open to the atmosphere, and the other connecting
- to the nozzle, and means for releasing a gaseous fluid under pressure into the tubular member in a stream substantially coaxial therewith.
5. In an oil burner, a rotatable oil cup, a nozzle surrounding the cup and forming a discharge passage past the cup for a blast of gaseous fluid, means utilizing the blast for rotating the cup, a tubular member having flaring ends, one of said ends being open to atmosphere and the other connected to the nozzle, and means for releasing a substantially coaxial stream of fluid under pressure into said tubular member.
6. In an oil burner, an oil cup, a rotatable sleeve supporting the cup, vanes on said sleeve whereby a blast of gaseous fluid may serve to rotate the cup, a nozzle for confining the space around the vanes and for directing a blast beyond the end of the cup so as to project the fuel therefrom into a combustion chamber, a tubular member connected to the nozzle for providing a continuous passageway therewith, said tubular member having a flared end adjacent the nozzle, a deflector for directing the fluid blast into the annular space between the nozzle and the rotatable sleeve, said tubular member having a free flaring end open to the atmosphere, a strap across this end, and means for releasing a stream of gaseous fluid under pressure into the tubular member, said means being supported on the strap.

In testimony whereof, I have hereunto set my hand.

HERBERT L. DELANEY.
